ATTORNEY

Patented Oct. 5, 1926.

UNITED STATES PATENT OFFICE.

LAURENCE ARTHUR VINCENT, OF PLEASANTVILLE, PENNSYLVANIA, ASSIGNOR TO
AMERICAN DRESSLER TUNNEL KILNS, INC., OF CLEVELAND, OHIO, A CORPOR-
ATION OF NEW YORK.

TUNNEL KILN.

Application filed June 28, 1923. Serial No. 648,199.

My present invention relates to continuous tunnel kilns of the muffle type, and more particularly to kilns of the Dressler type, which are heated by combustion chambers which are located at the sides of the goods' pathway and formed with channels in their walls for setting up a directed convection current circulation of the kiln atmosphere, whereby heat is transferred from the combustion chambers to the goods, and the walls of the combustion chamber are protected against overheating; and the general object of my invention is to provide improvements tending to a better circulation of the kiln atmosphere.

The various features of novelty which characterize my invention are pointed out with particularity in the claims annexed to and forming a part of this specification. For a better understanding of the invention, however, and its advantages, reference should be had to the accompanying drawings and descriptive matter in which I have illustrated and described preferred embodiments of my invention.

Of the drawings;

Fig. 1 is a somewhat diagrammatic sectional plan;

Fig. 2 is a transverse section on the line 2—2 of Fig. 1;

Fig. 3 is a transverse section on the line 3—3 of Fig. 1; and

Fig. 4 is a section on the line 4—4 of Fig. 1.

In the drawings, A represents the kiln chamber which is widened at about the level of the tops of the car bodies C thereby providing benches B on which are mounted the combustion chambers D, the conduit extensions F thereof at the entrance end of the kiln, and the air cooling pipes G adjacent the exit end of the kiln. As shown the combustion chambers each receive fuel as gas through one or more burner nozzles H, and each receives air for the combustion of the fuel directly from the kiln chamber through ports HA. The air passing into the combustion chamber may enter the kiln chamber through ports A¹⁰ at the exit end of the kiln and this air supplements the kiln cooling effect of the pipes G. As shown the ports A¹⁰ are formed in the exit door of the

kiln chamber. The products of combustion are drawn from the combustion chambers D through the pipes F, and are passed from the latter through suitable ports at the entrance end of the kiln into a valve controlled conduit I, by a suitable draft creating device shown as a stack J. The walls of each combustion chamber are formed of hollow tile sections E, E', E² and E³, each of which extends transversely to the length of the kiln chamber, and each of which is formed with a plurality of longitudinal channels e. The various sections E, E', E² and E³, which are formed of refractory material as fire clay or carborundum, are shaped to fit together as shown in Fig. 2, so that the channels e in the various tile sections E, E', E² and E³ unite to form flues open to the kiln chambers at the ends of the bottom sections E and at the upper ends of the sections E³. In operation the kiln atmosphere in the channels e is heated above the average kiln atmosphere temperature in the adjacent portions of the kiln chamber and this creates a convection current circulation of the kiln atmosphere as indicated by the arrows in Fig. 2. The cooling pipes G communicate with the atmosphere at the exit end of the kiln through ports G' and adjacent the combustion chambers D. The pipes G are connected to headers or end chambers G² which communicate through ports G³ and a flue G⁴ with a suitable draft creating device (not shown) for drawing air into the pipes G through the ports G', and for drawing this air out of the pipes G through the headers G', ports G³ and flue G⁴. Insofar as above described the kiln illustrated contains nothing novel with me, but on the contrary is a well-known form of Dressler kiln in extensive use.

The combustion chambers illustrated differ from those heretofore employed in two respects. One of these differences arises from the fact that I make the vertical depth of each channel e in the horizontal bottom tile sections E and preferably also in the top section E³, substantially greater than the corresponding dimension of the channels e in the side tile sections E' and E², whereas it has heretofore been the practice to make all of the tile sections employed in my par-

ticular combination chamber exactly similar in transverse section dimensions. While the invention, of course, is not limited to any exact dimension or proportion, it may facilitate an understanding of the invention to point out that in ordinary kilns I propose to make the vertical depth of the channels in the sections E and E² 8 inches, and to make the corresponding dimensions of the channels e in each of the sections E' and E², 6 inches.

The second difference between the combustion chambers illustrated, and those heretofore employed, is found in the fact that the bottom tile sections E project into the kiln chamber past the lower ends of the inner side sections E', and past the inner sides of the corresponding benches B, into grooves C' formed in the sides of the cars beneath the goods supporting platform C² of the cars and in close proximity to the ends of the transverse circulation channels C³ formed in the wall portions of the car bodies immediately beneath the platforms C² which are usually perforated to permit the circulation of the kiln atmosphere down through the goods X on the car platforms into the tops of the channels C³.

The above noted differences between the combustion chamber construction and arrangement disclosed, and the practice heretofore followed, each contribute to a more intense and better distributed kiln atmosphere circulation. In particular the greater depth of the channels e in the bottom and top sections E and E² tend to increase the upflow through the channels e in the outer sections E², and more nearly equal to the upflow through the channels e in the sections E than has been the case with the constructions heretofore employed, thus improving the heat transfer and avoiding a sometimes undesirable tendency for the outer wall sections E² of the combustion chamber to become appreciably hotter than its inner wall sections E'.

The extension of the inner ends of the bottom sections E under the side edges of the car platforms and in close proximity to the channels C³, also tends to a more vigorous circulation of the kiln atmosphere and a better distribution of the descending current of the kiln atmosphere through the portion of the kiln chamber traversed by the goods.

The kiln illustrated also differs from kilns of the same general type heretofore employed, in that provisions are made for withdrawing a portion of the kiln atmosphere from the kiln chamber adjacent the entrance end of the latter and at approximately the level of the bottom of the goods pathway. The provisions shown for this purpose comprise ports K and KA. The ports K open at the tops of the benches B adjacent their inner edges and are connected through a

conduit K' to the stack J. The ports KA open from the antechamber A²⁰ of the kiln at about the level of the tops of the benches B into vertical channels K⁵ which are connected through a conduit K⁶ to the stack J. The conduits K' and K⁶ are each provided with a damper K². In practice air may be withdrawn from the kiln chamber exclusively through the ports K, or exclusively through the ports KA, or partly through the ports K and partly through the ports KA, as conditions make desirable. The withdrawal of a small quantity of the kiln atmosphere through ports located as are the ports K and KA is desirable in any form of muffle kiln in which a draft suction is impressed on a central portion of the kiln chamber, such as is impressed in the kiln illustrated, by the ports HA through which the combustion chambers D are supplied with air for combustion from the kiln chamber. The withdrawal of the kiln atmosphere from the exit end of a muffle heated kiln tends to eliminate an otherwise objectionable longitudinal circulation in the kiln chamber which is generally undesirable and in the case of the Dressler type of kiln illustrated is especially objectionable, as it interferes with the desired transverse circulation through the channels e in the walls of the combustion chambers. This feature of my invention is especially advantageous in the case of a kiln employed in burning bricks or other coarse clay products as it draws out of the kiln chamber a good deal of the steam or water-smoke driven out of the goods in their initial heating up, and prevents the steam or water-smoke passing into the high temperature portion of the kiln chamber. The elimination of steam or water-smoke in this manner tends to reduce the fuel consumption of the kiln, and makes it easier to hold the heat, and tends to a better firing of the lower portions of the masses of goods stacked on the cars.

While in accordance with the provisions of the statutes, I have illustrated and described the best forms of my invention now known to me, it will be apparent to those skilled in the art that many changes may be made in the form of the apparatus disclosed without departing from the spirit of my invention as set forth in the appended claims, and that certain features of my invention may sometimes be used with advantage without a corresponding use of other features.

Having now described my invention, what I claim as new and desire to secure by Letters Patent, is:

1. In a continuous tunnel kiln provided with closed combustion chambers at the sides of the goods pathway through the kiln, from which heat is transferred to the ware passing through the kiln mainly by a transverse convection circulation of the kiln at

mosphere, the improvement which consists in means for exerting a kiln atmosphere exhausting effect at the ware entrance end of the kiln adjacent the bottom level of the goods pathway therethrough.

2. In a continuous tunnel kiln the combination with goods carrying cars formed with goods supporting platforms projecting at the sides of the cars beyond the subjacent portions of the cars and also formed with transverse channels having open ends at the sides of the cars below said platforms and communicating through the platforms with the space above the latter, and combustion chambers at the sides of the cars, the bottom walls of which are formed by tile sections transverse to the length of the kiln with their inner ends extending under the projecting edges of the car platforms and provided with longitudinally extending open ended channels and other tile sections forming the

upper portions of the walls of the combustion chambers and formed with channels uniting with the channels in the bottom tile sections to form a flue system open to the kiln chamber through the channels in the bottom section and at the top of the combustion chambers.

3. In a tunnel kiln having muffle heating provisions comprising means for exerting a kiln atmosphere exhausting effect in a high temperature portion of the kiln chamber, the improvement which consists in means for exerting a second kiln atmosphere exhausting effect at the ware entrance of the kiln adjacent the bottom level of the goods pathway therethrough.

Signed at Cleveland, in the county of Cuyahoga and State of Ohio, this 23rd day of June, A. D., 1923.

LAURENCE ARTHUR VINCENT.
